UNITED STATES PATENT OFFICE.

GEORGE H. PERKINS, OF PHILADELPHIA, PENNSYLVANIA, ASSIGNOR OF
ONE-HALF TO THE ATLANTIC REFINING COMPANY, OF SAME PLACE.

APPARATUS FOR FILLING CANS.

SPECIFICATION forming part of Letters Patent No. 519,307, dated May 1, 1894.

Application filed December 28, 1893. Serial No. 494,942. (No model.)

To all whom it may concern:

Be it known that I, GEORGE H. PERKINS, a citizen of the United States, residing in the city and county of Philadelphia and State of Pennsylvania, have invented certain new and useful Improvements in Apparatus for Filling Cans, of which the following is a specification.

In filling cans with petroleum it is desirable that the inflowing stream of oil should be of large size so that the filling may be expeditiously accomplished, and it is customary to provide the can with an inlet opening of diameter greater than that of the stream so as to afford an outlet for the air displaced by the oil. In practice, however, it is found that the foaming occasioned within the can by the volume and impetus of a large entering stream results in the splashing or overflow of a portion of the liquid through the said air outlet when the level of the oil approaches the top of the can, and renders it difficult to fill the can exactly full. It has been attempted to remedy the difficulty by charging a stream of a given size into a can until the latter is nearly full, and by then partially closing the pipe or conduit through which the stream flows, so that thereafter, the size of the stream of oil flowing into the can being diminished, the amount of foaming within the can will be correspondingly decreased. Such a diminished stream of oil, however, in descending through and issuing from the relatively large vertical pipe through which it flows, does not follow a directly vertical course, but flows over different portions of the inner face of the pipe, and, crawling outwardly across its lower edge, tends to discharge eccentrically and irregularly in different directions, with the result, the pipe not entering the can but terminating a short distance above it, that a quantity of the oil lodges upon the exterior of the can.

It is the object of my invention to provide an apparatus by which a large volume of oil may be rapidly charged to a can or kindred receptacle until the latter is nearly full, and by which a small stream of oil may thereupon steadily, accurately, and in such manner as not to occasion foaming or overflow, be charged to the can until the latter is precisely full.

In the accompanying drawings I show and

herein I describe a good form of a convenient embodiment of my invention, the particular subject matter claimed as novel being hereinafter definitely specified.

55

In the accompanying drawings, Figure 1 is a view in side elevation, and Fig. 2 a central, vertical, partly sectional, elevation, of an oil reservoir equipped with a good form of my invention. Figs. 3 and 4 are vertical, partly 60 sectional, elevational views of my improved oil valve as mounted within the reservoir, illustrating respectively different positions of the parts.

Similar letters of reference indicate corresponding parts.

In the drawings, A is what I hereinafter term a reservoir, the same being a receptacle of any desired general character, shown however as an upright vessel of cylindric contour, the upper end of which is open, and the lower end a^x of which consists of a depending funnel-shaped bottom having a central discharge opening or mouth, the interior of which bottom tapers from the vertical wall of 70 the reservoir, to a diameter, at its mouth a' , corresponding to that of a conduit B, the upper extremity of which is permanently fitted within said mouth. The conduit B is of any appropriate length, and beneath it the cans to 75 be filled are successively placed with their receiving apertures in alignment with its axis.

D is what I term a reserve funnel, the same being a containing receptacle, adapted to hold a predetermined quantity of oil, contained 80 within and adapted to have vertical movement with respect to the reservoir A. The reserve funnel consists of an open-topped cylindrical body designated d^x , having a downwardly tapering bottom designated d , the 85 lower or exterior face of which is of such proportions and inclination as to adapt it to accurately and snugly fit within the funnel-shaped bottom of the reservoir A. The tapering bottom d of the reserve-funnel embodies a central aperture d^2 , within the lower 90 part of which is fitted the upper extremity of a pipe D^x of considerably smaller diameter than, but supported in a position axial with respect to, the conduit B hereinbefore referred to.

d' is a spider frame mounted upon and se-

cured to the upper portion of the reserve funnel, and serving to support an annular head plate d^3 in axial alignment over the aperture d^2 in the bottom of said funnel.

- 5 E is a valve head, fitted to the aperture d^2 which constitutes its seat,—and provided with a valve stem F which extends upward through the opening in the annular head plate d^3 . Upon the valve stem a short distance above its head E, is formed a boss, enlargement or projection F^x , which, in the elevation of the said stem, is adapted to encounter the annular head plate and occasion the elevation of the reserve funnel.
- 15 The spider d' , head plate d^3 , and boss F^x , constitute a connection between the valve stem and the reserve funnel.

The valve stem may be operated in any desired manner. The arrangement illustrated

- 20 in Figs. 1 and 2 of the drawings is, however, adapted to the purpose and one which I prefer to employ.

G is a windlass wheel having a crank handle g , and mounted with its axis horizontal 25 in such position within the reservoir that its periphery is in line above the valve stem, and G^x is a flexible connection between said stem and windlass. By the throw of the handle g in one or the other direction, the elevation 30 or depression of the valve stem will be occasioned.

In the drawings I have shown the reservoir as provided with an enlargement H to receive the wheel G.

- 35 The operation of the device is as follows:—The reserve funnel being supposed in the position illustrated in Fig. 2, and it being assumed that the reservoir is full of oil and that a can to be filled and adapted to contain a quantity of 40 oil equal to the quantity contained in the reservoir, has been placed in position beneath the reservoir, it will be understood that the elevation of the valve stem F will first withdraw the valve head from its seat, and will then, 45 by the encounter of the boss F^x with the head plate d^3 , lift the reserve funnel from the bottom of the reservoir so that the parts will occupy the positions illustrated in Fig. 3. When the parts are in such positions, a full head of 50 the oil within the reservoir will be discharged through the conduit B and pipe D^x into the can beneath, and the liquid level within the reservoir will be steadily and uniformly lowered. After, however, the liquid within 55 the reservoir has been reduced to the level of the top of the reserve funnel, said liquid level, in the further escape of the liquid, will not be uniformly lowered, for the reason that,—the area of the interior of the reserve 60 funnel being greater in proportion to the diameter of the pipe D^x than is the area of the space exterior to said reserve funnel to the diameter of the conduit B,—the level of the liquid exterior to the reserve funnel will fall 65 much more rapidly than the level of the liquid within said funnel, with the result that, after all the liquid exterior to the funnel has

escaped through the conduit B, a quantity of liquid will still remain in the funnel to escape only through the relatively small pipe D^x . 70

In Fig. 3 of the drawings the line $w-w$ indicates the liquid level at the end of, say, five seconds after the oil commences to discharge through the conduit B; the line $x-x$ indicates said level at the end of, say, ten 75 seconds; and the line $y-y$ indicates said level at the end of, say, fifteen seconds.

As hereinbefore described, it is desirable in the filling of the can to charge a large stream thereto until the oil within the can reaches 80 a certain intermediate level in proximity to the top of the can, and thereafter to avoid the splashing and overflow of the oil, to charge into the can, in a small and steady stream, the balance of the oil which said can is to 85 contain.

In my apparatus illustrated and described herein, by predetermination of the capacities of the reservoir and the reserve funnel with relation to the capacity of the can, the 90 said intermediate level in the can is reached by the oil therein when all the oil in the reservoir exterior to the reserve funnel has been discharged into said can, and, when this condition has been established, as will be understood, the oil remaining in the reserve funnel,—which is sufficient to complete the filling of the can,—will descend through the small pipe D^x alone, in a stream which, although 95 small, will yet be the full diameter of said 100 pipe D^x , and will therefore be discharged directly and accurately through the center of the can opening.

The parts illustrated, as will be understood, occupy the position shown in Fig. 2 during 105 the operation of charging into the reservoir the oil or other liquid to be subsequently charged to the can, the valve and reserve funnel being so related to each other, and the reserve funnel so related to the bottom of the 110 reservoir, that a liquid-tight closure of the bottom of the reservoir is effected. After a can has been placed in position beneath the reservoir,—the valve stem F is, by the throw 115 of the handle g , elevated, and in its elevation, operates first to withdraw the valve head from its seat within the outlet of the reserve funnel, and, second, by the encounter of the boss 120 F^x with the annular head plate, as shown in Fig. 4, to elevate the reserve funnel to the 125 position illustrated in Fig. 3, to allow of the discharge of the oil at first through both the conduit B and pipe D^x , and, subsequently, after the intermediate liquid line in the receiving can has been reached, through the 130 pipe D^x alone.

Having thus described my invention, I claim—

1. In combination, a reservoir embodying a discharge liquid outlet, and a reserve funnel embodying a discharge outlet smaller than that of the reservoir and in alignment with it, said funnel being mounted within the reservoir, substantially as set forth.

2. In combination, a reservoir, embodying a liquid discharge outlet, a reserve funnel mounted within the reservoir and embodying a discharge outlet smaller than that of the reservoir, and a liquid valve head fitted to the outlet of said funnel, substantially as set forth.
3. In combination, a reservoir embodying a discharge outlet, a reserve funnel embodying a discharge outlet smaller than that of the reservoir, said funnel being externally adapted to the discharge outlet of the reservoir, a valve head fitted to the discharge outlet of the reserve funnel, and means for occasioning the withdrawal of the valve head from the outlet of the funnel and the withdrawal of the funnel from the outlet of the reservoir, substantially as set forth.
4. In combination, a reservoir having a funnel shaped bottom embodying an outlet, a reserve funnel having an imperforate upwardly extending wall, and provided with an outlet and externally adapted to the outlet of the reservoir, a valve head fitted to the outlet of the funnel, means for withdrawing the valve head from the outlet of the funnel and for supporting the funnel above and clear of the bottom of the reservoir, substantially as set forth.
5. In combination, a reservoir embodying a discharge outlet,—a reserve funnel provided with an outlet, the lower portion of which funnel is adapted to fit within the outlet of the reservoir,—a valve head adapted to fit within the outlet of the reserve funnel,—a valve stem, connected with the reserve funnel,—and means for operating said stem, substantially as set forth.
6. In combination,—a reservoir provided with a discharge outlet,—a conduit leading from said outlet,—a reserve funnel provided with an outlet, the lower portion of which funnel is adapted to fit within the outlet of
- the reservoir,—a pipe fitted to said reserve funnel axially with respect to the conduit of the reservoir,—a stem provided with a head adapted to the outlet of the reserve funnel, and with means for engaging with the upper portion of the reserve funnel,—and means for operating said valve stem to occasion the withdrawal of its head from the outlet of the reserve funnel and the elevation of the said reserve funnel,—substantially as set forth.
7. In combination,—a reservoir provided with a discharge outlet,—a reserve funnel provided with an outlet,—a stop or head plate supported upon the upper portion of the reserve funnel,—a valve stem provided with a head adapted to the outlet of the reserve funnel and with a boss adapted to engage the stop or head plate,—and means for operating said valve stem,—substantially as set forth.
8. In combination, a reservoir provided with a discharge outlet,—a conduit fitted in said outlet,—a reserve funnel the lower portion of which is adapted to the outlet of the reservoir and provided with an outlet,—a pipe fitted to said outlet,—a head plate supported upon the upper portion of the reserve funnel,—a valve stem provided with a head adapted to the outlet of the reserve funnel and with a boss to engage the head plate,—and means for operating said valve stem,—substantially as set forth.
9. In combination, the reservoir, the reserve funnel, the valve head, the valve stem connected with said reserve funnel, the windlass, and the connection between the windlass and the valve stem, substantially as set forth.

In testimony that I claim the foregoing as my invention I have hereunto signed my name this 26th day of December, A. D. 1893.

GEORGE H. PERKINS.

In presence of—

EDWIN ALAN PERKINS,
J. BONSALL TAYLOR.
